(57) **CLAIM**

The ornamental design for a radar array, as shown and described.

DESCRIPTION

FIG. 1 is a top perspective view of a radar array;
FIG. 2 is a front view of the radar array;
FIG. 3 is a top view of the radar array;
FIG. 4 is a rear view of the radar array;
FIG. 5 is a bottom view of the radar array;
FIGS. 6 and 7 provide side views of the radar array; and,
FIG. 8 is a bottom perspective view of the radar array.
Features shown in broken lines in the Figures are provided for illustrative purposes and are not part of the claimed invention.
